Primary Examiner — Karen S Acker*Assistant Examiner* — Jonathan E Fiencke(74) *Attorney, Agent, or Firm* — Wolf, Greenfield & Sacks, P.C.(57) **CLAIM**

The ornamental design for a nozzle head, as shown and described.

DESCRIPTION

FIG. 1 is a top perspective view of a nozzle head, in accordance with the present design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof; and,

FIG. 7 is a bottom plan view thereof.

The broken lines depict portions of the nozzle head that form no part of the claimed design.
